D10-129. OR D 18,821 EX

DESIGN.

C. W. WARD.

WATCH BRIDGE.

No. 18,821.

Patented Dec. 18, 1888.

UNITED STATES PATENT OFFICE.

CHARLES WILLIS WARD, OF YONKERS, NEW YORK.

DESIGN FOR A WATCH-BRIDGE.

SPECIFICATION forming part of Design No. 18,821, dated December 18, 1888.

Application filed November 7, 1888. Serial No. 290,241. Term of patent 7 years.

To all whom it may concern:

Be it known that I, CHARLES WILLIS WARD, a citizen of the United States, residing at Yonkers, in the county of Westchester, State 5 of New York, have invented and produced a new and original Design for Watch-Bridging; and I do hereby declare the following to be a full, clear, and exact description of the same, reference being had to the accompanying 10 engraving, forming a part thereof.

My invention relates to a new and original design for watch-bridging; and it consists in the particular arrangement and ornamental shaping of the several parts, resulting in the 15 production of the attractive and artistic bridge hereinafter described and claimed.

In the accompanying engraving, forming part of this specification, A designates the outer casing or rim, and B, C, D, E, and F the 20 respective parts constituting, in connection with the balance-cock G, the bridge of the watch.

The part B is located in the lower portion 25 of the casing, it spanning the interior thereof from points near its lower sides, the abutting ends being curved to conform to the contour of the rim. The lower side of this part is straight, and the upper side is formed parallel with the lower, its left-hand corner or end 30 curving slightly upward and then obliquely downward, forming an angle or corner. The end of this part to the right is curved inwardly and extends downward and beyond the parallel sides to the rim, the upper side being straight and the lower side curved outwardly, thereby increasing the width of the 35 lower or contacting edge portion.

The part C is located to the right and above

the part B. It projects from the rim inward, its lower edge inclining obliquely upward and 40 its upper edge being arched or curved upwardly, and terminating in a point. The inner edge of this part is formed in a double curve, the lower part being carried out and forming a continuance of the lower edge, while 45 the upper curve is carried in, forming an angle at the junction with the lower curve.

The central part, D, is serpentine in shape, and extends from the rim on the right a short distance above the part C to a point near the 50 opposite side of the casing, its lower inner end coming in proximity to the upper side of the end of part B.

The parts E and F are short and curve obliquely downward from the upper side of the 55 rim, and are separated from each other by an intervening space. The part E is also separated from the part D by an intervening space.

The balance-cock G is placed on the left- 60 hand side, and extends obliquely upward into the space between the upper parts and the rim. By this arrangement an artistic, graceful, and attractive bridge is produced.

Having thus described my invention, what 65 I claim as new, and desire to secure by Letters Patent, is—

The design for a watch-bridge, substantially as herein shown and described.

In testimony whereof I affix my signature in 70 presence of two witnesses.

CHARLES WILLIS WARD.

Witnesses:

LYELL T. ADAMS,
E. T. GILLILAND.
